UNITED STATES PATENT OFFICE

165,397

DRESSER OR SIMILAR ARTICLE

Otis C. Robbins, Dallas, Tex.

Application February 23, 1950, Serial No. 8,077

Term of patent 3½ years

(Cl. D33—6)

To all whom it may concern:

Be it known that I, Otis C. Robbins, a citizen of the United States, residing at Dallas, in the county of Dallas and State of Texas, have invented a new, original, and ornamental Design for a Dresser or Similar Article, of which the following is a specification, reference being had to the accompanying drawing, forming part thereof.

Figure 1 is a front perspective view of a dresser or similar article embodying my new design;

I claim:

The ornamental design for a dresser or similar article, substantially as shown.

OTIS C. ROBBINS.
